OIL CAN WITH CENTER OPERATING HANDLE

John B. Swan, Gladstone, Mich.

Application July 21, 1942, Serial No. 451,787

4 Claims. (Cl. 221—46)

This invention relates to an oil can or oiler, with a center operating handle.

An object of this invention is the construction of a simple and efficient oil can or oiler which is provided with a pivoted lever handle over the fixed handle of the container, whereby the device can be easily operated either by a right or left-hand person.

Another object of the invention is the construction of a valve device that is positioned close to the discharge end of the spout of an oiler, whereby the oil flowing from the can can be efficiently cut off promptly, thereby saving oil.

A further object of the invention is the production of an oil can which is easily operated, and which will save oil, as well as being comparatively inexpensive to manufacture.

With the foregoing and other objects in view, my invention comprises certain novel constructions, combinations, and arrangements of parts as will be hereinafter fully described, illustrated in the accompanying drawing, and more particularly pointed out in the appended claims.

In the drawing:

Figure 1 is a view partly in elevation and partly in vertical section of an oil can or oiler constructed in accordance with the present invention.

Figure 2 is a horizontal section taken on line 2—2, Figure 1, and looking in the direction of the arrows.

Figure 3 is an enlarged fragmentary sectional view of the spout, showing the valve device therein.

Figure 4 is an enlarged sectional view taken on line 4—4, Figure 1, and looking in the direction of the arrows.

Figure 5 is an enlarged fragmentary vertical sectional view of the valve device.

Figure 6 is a sectional view taken on line 6—6, Figure 5, and looking in the direction of the arrows.

Referring to the drawing, in which I have shown the preferred embodiment of my invention, 1 designates a container which is provided with a fixed handle 2. The container 1 is provided with a long spout 3; this spout comprises a long inner unit 4 and a short outer unit 5.

Within the container 1 and spout 3 is an air-vent device 6, which device 6 is fully illustrated and specifically described in my co-pending application Serial Number 420,032 filed November 21, 1941.

A container tube 7 is extended through inner unit 4 of the spout 3 at 8; at point 8 said tube 7

is preferably soldered, or otherwise suitably secured in position upon the spout. The inner end of tube 7 within the inner unit 4 is positioned in a spaced relation to the inner walls of unit 4, so that oil within container 1 can pass freely the inner end of the tube 7. On the inner end of tube 7 is an enlarged shoulder 9, which shoulder is provided with an inner flat face 10 upon which face normally is seated a cone washer 11 that is preferably made of yieldable material such as leather or the like. This cone washer 10 seals the tube 7 against any liquid, such as oil, passing down tube 7 to the outer atmosphere. A relatively strong yet yieldable wire 12 extends through tube 7, as well as through washer 11, and is fixedly secured at its outer end within a valve head 13. This head 13 is normally seated against valve seat 14; seat 14 being formed in the inner end of externally threaded coupling 15. The contiguous ends of units 4 and 5 are threaded upon coupling 15 as is clearly seen in Figure 5. Coupling 15 is provided with a central passage 16, through which the oil of the can may pass.

A metal cone cap 17 is mounted upon wire 12 and rests against the cone washer 11. One end of outer spring 18 is seated on cone cap 17 as well as one end of inner spring 19. The ends of springs 18 and 19 opposite to the ends engaging cone cap 17 bear against the flat inner end of valve head 13. These springs produce an efficient result by causing the valve head 13 to seat, to cut off the flow of oil, as soon as the operator releases or disengages the pivoted lever handle 20.

The lever handle 20 is provided with flanged edges 21 (see Fig. 4) which produce an efficient grip to be engaged by the hand. This lever handle is positioned in alignment with and directly above the fixed handle 2, whereby either a right-hand or left-hand person can quickly grasp the fixed handle 2 and manipulate the lever handle 20, thereby eliminating the necessity of two oil cans as has been heretofore required for a left-hand or right-hand operator.

The pivoted lever handle 20 is mounted on pin 22 which extends through a sleeve 23; this sleeve 23 is integral with handle bracket 24. Bracket 24 is suitably secured to the inner unit 4 near container 1. The outer end of wire 12 extends through aperture 25 of handle 20 and an eye 26 is formed on the wire 12, between the flanges 21, and a cotter pin 27 extends through eye 26, securely fastening the wire 12 and handle 20 together.

A substantially V-shaped bracket 28 has its feet 29 fixedly secured to the inner unit 4 of

spout 3 and on the outer end of bracket 28 is an integral eye 30, through which eye 30 extends the container tube 7. The eye 30 and tube 7 are fixedly secured together as by soldering or welding, whereby the tube 7 is rigidly supported at its outer end upon spout 3.

In operation, when the operator presses downwardly upon the lever handle 20, this will cause wire 12 to be drawn outwardly, against the action of the double springs 18 and 19, whereupon the valve head 13 is moved away from its seat 14, thereby opening passage 16 to allow the oil to flow from the container through the spout. As soon as the valve head 13 is moved away from its seat 14, the air-vent device 6 will allow air to rush into the spout, whereby prompt flowing of oil through the spout is obtained. The valve device, being placed near the discharge end of the spout, prevents waste of oil, because of the nearness to the end of the spout and instant action of the seating of the valve head, as soon as the operator releases the lever handle 20. This results in a great saving of oil. The wire 12, while of sufficient flexibility to allow sliding action through container tube 7, is sufficiently rigid to maintain an excellent action in manipulating the valve device of which it is a part.

The novel metal cone cap 17 performs two functions, to wit: It extends substantially into the ends of the double springs, affording an excellent bearing for said springs, and the pressure of the springs on the cone causes the cone to press or clamp upon the yieldable washer 11, thereby sealing tube 7 against any back-flow of the oil through tube 7. This produces a very efficient construction, among the other advantages of my device, such as the central positioning of the lever handle over the fixed handle, and the nearness of the cut-off valve to the discharge end of the spout, involving a great saving in oil from being wasted when the operator discontinues using the oil can.

While I have described the preferred embodiment of my invention and illustrated the same in the accompanying drawing, certain minor changes or alterations may appear to one skilled in the art to which this invention relates, during the extensive manufacture of the same, and I, therefore, reserve the right to make such alterations or changes as shall fairly fall within the scope of the appended claims.

What I claim is:

1. In a device of the class described, the combination with a container provided with a spout, of a substantial V-shape bracket provided with feet engaging said spout, said V-shape bracket being provided with an eye on its outer end, a container tube within said eye, said container

tube extending into said spout, valve means within said spout and including a wire, said wire extending through said container tube and beyond its outer end, and manually operated means connected to said spout and movably connected to the outer end of said wire.

2. In a device of the class described, the combination with a container provided with a spout, said spout comprising an inner long unit and an outer short unit, of an externally threaded coupling on the contiguous ends of said inner and outer units, said coupling provided with a passage and with a valve seat on its inner end, a container tube extending into said inner long unit, said tube being provided with an enlarged shoulder on its inner end, said shoulder having a flat outer surface, a yieldable conical washer resting against said flat surface, a metal cone cap resting on said cone washer, a wire extending through said container tube, said wire provided on its inner end with a valve head, said valve head normally seated against the valve seat of said coupling, an inner and an outer coil spring around said wire, the outer ends of said springs bearing against said valve head and the inner ends of said springs bearing against and seated upon said metal cone cap, said wire extending beyond the outer end of said container tube, and manually operated means connected to the outer extended end of said wire, substantially as shown and described.

3. In a device of the class described, the combination with a container provided with a spout, of an outlet valve device in said spout and including a hollow cone cap, said outlet valve device also including springs bearing against said cone cap, a container tube extending into said spout and provided with a shoulder, a yieldable washer extending into said cone cap and bearing against a portion of said shoulder whereby the tube is sealed against back-flow of oil, and manually operated means extending through said container tube and connected to said outlet valve device for operating said device.

4. In a device of the class described, the combination of an oil can provided with a spout, a container tube extending substantially parallel with said spout and into said spout near its outer end, said spout including a coupling, a valve head engaging and normally closing said coupling, a washer and a cap thereover normally closing the inner end of said container tube, manually-operated means including a wire, said wire extending through said container tube, washer, and cap and connected at its inner end to said valve head, and spring means on said wire and pressing directly upon said valve head and cap.

JOHN B. SWAN.
